H. J. BAILEY,
MUSIC LEAF TURNER,
APPLICATION FILED OCT. 6, 1914.

1,219,904.

Patented Mar. 20, 1917.

UNITED STATES PATENT OFFICE.

HERBERT JOHN BAILEY, OF TRENTON, NEW JERSEY.

MUSIC-LEAF TURNER.

1,219,904.

Specification of Letters Patent. Patented Mar. 20, 1917.

Application filed October 6, 1914. Serial No. 865,235.

To all whom it may concern:

Be it known that I, HERBERT JOHN BAILEY, a subject of the King of Great Britain, and a resident of Trenton, in the county of Mercer and State of New Jersey, have invented 5 a new and Improved Music-Leaf Turner, of which the following is a full, clear, and exact description.

This invention relates to musical instruments and has particular reference to devices 10 for holding and automatically turning the leaves of sheet music.

Among the objects of the invention is to provide a construction of the simplest character and adapted to be secured either upon 15 a music rack of ordinary nature or upon a piano casing or other stationary support.

A further object of the invention is to provide a means of the character set forth which 20 will hold the music leaves securely and yet not damage the same.

The foregoing and other objects of the invention will hereinafter be more fully described and claimed and illustrated in the 25 drawings forming a part of this specification in which like characters of reference indicate corresponding parts in all the views, and in which—

Figure 1 is a front elevation of the improvement shown as attached to a common 30 form of tripod music rack;

Fig. 2 is a plan view of the improvement; and

Figs. 3, 4 and 5 are vertical transverse sections on the corresponding lines of Fig. 2.

The several parts of this device may be made of any suitable materials, and the relative sizes and proportions, as well as the 40 general design of the mechanism, may be varied to a considerable extent without departing from the spirit of the invention hereinafter more fully described and specifically claimed.

Referring more particularly to the drawings I show a main body 10 which carries 45 the operating parts and constitutes the main member of a clamp adapted to secure the device detachably to any desired object. The other member of the clamp is shown as a substantially flat plate 11 coöperating with 50 the upper surface of the body 10, and a screw or bolt 12 rigidly connected at its head 12' to the plate 11 passes downwardly through the body whereby, through the action of a winged nut 13 or the equivalent, the plate 55 11 is caused to approach the body and grip

securely the flange 14 of the music rack as indicated.

This device is preferably locked or gripped to the flanges 14 of the two wing portions of the music rack substantially at the center of the music rack, the bolt 12, as shown in Figs. 1 and 4, coming between the adjacent ends of the flanges 14, and by the action of the clamp members the music rack is stiffened 60 and made more substantial for the purposes for which it is intended. Obviously the clamp members 10 and 11 may be separated as far as necessary so as to engage the projecting lip or flange of any suitable stationary object such, for instance, as the music rail of a piano or the like.

The front face of the main body 10 is rabbed so that a step is formed at the lower portion which projects forwardly beyond 70 the upper portion thereof; upon this step and to the rear of the plane of the vertical face of said step is mounted the operating mechanism of the device.

Each leaf or page of music, indicated in 80 dotted lines in Fig. 1 at 15, is adapted to be placed upon and carried by an arm 16 mounted upon a substantially vertical pivot 17 mounted on the step of the body 10 and movable around the said pivot through an angle 85 of substantially 180 degrees. To each of the arms is secured a peculiar form of clip 18 shown best in detail in Fig. 5. Each of these clips is composed preferably of sheet spring metal of a suitable width and looped to embrace the arm 16. The free ends of the strip of metal are of different lengths and are adjusted close together just above the edge of the arm 16, the longer end or finger being in the rear or adjacent the rear 90 surface of the sheet support therein. A screw 19 or its equivalent coöperates with the two finger portions of the clip to cause the clip to grip the arm at any desired distance from the pivot 17 and also to vary the 95 width or gripping effect of the space between the two fingers above the screw. As above premised, the clips 18 may be set at any desired distance apart or at varying distances from the pivot 17, depending upon the size 100 or character of the music sheets.

In preparing the device for turning the music, the arms 16 are swung toward the right and each of them is there held by means of a trigger 20 of a nature shown best 110 in Fig. 3. Each trigger is locked in the body 10 by means of a screw 21 acting up-

wardly from the bottom of the body through a hole 22. The trigger member projects thence forwardly through a recess or notch 23. The rear end of the trigger is set rigidly in the rear end of the notch where it is locked by the screw 21, and the front portion of the notch is flared downwardly so as to provide free space for the finger piece or front end of the trigger to operate downwardly. The shank 24 of the trigger constitutes a comparatively thin spring so as to permit sufficient flexibility to allow the catch or shoulder 25 thereof to engage over a wing 26 constituting a portion of the arm 15 along its lower edge adjacent the pivot. A spring 27 of any suitable nature, but indicated as a coil spring wound around the pivot 17, tends to cause each arm to swing toward the left when released from the 20 shoulder 25 of the trigger upon the depression of the front portion of the trigger. When the arms 16 are swung toward the right, however, the wing portions 26 thereof slide over the shoulders 25 and the triggers 25 catch automatically to hold the arms at the right hand side with the springs under tension.

Obviously any desired number of these pivoted or swinging arms 16 may be employed, but by way of illustration I show two thereof. These arms are arranged to swing in substantially the same plane, or, in other words, the upper edges of the arms move in the same plane. The trigger mechanisms, however, are arranged in planes one slightly above the other so as to insure that the trigger at the left, or pertaining to the arm in front of the other, will not obstruct nor interfere with the free swinging movement of the rearmost arm. In other words, when the parts are arranged and set in the position illustrated in Figs. 1 and 2, the trigger at the left is adapted to be depressed to release the first arm, allowing it to swing 40 around to the left, the other arm remaining in the position shown until its trigger is subsequently depressed. When the latter mentioned trigger is depressed, the arm held thereby will be released and the wing 26 thereof will swing freely over the left hand trigger. Obviously then the left hand trigger will not interfere with the free swinging movement of the rearmost arm around to the right. 50 To the arms 16 are connected as many stiff standards 28 as may be desired. These standards lie in the rear of the music leaves and hence constitute the main supports therefor in holding the music leaves or caus-

ing them to swing around. These standards 60 are preferably pivoted at 29 to the arms so as to be moved into substantial alinement with the arms for the purpose of folding up the device for transportation. These standards, furthermore, are preferably made of 65 celluloid or other transparent material so as not to interfere with the reading of the music upon the turned page.

Having thus described my invention, I claim as new and desire to secure by Letters 70 Patent:—

1. A music leaf turner comprising a main body portion or support having a rabbeted front face forming a step at its lower end, leaf carrying arms pivoted at one end on 75 vertical pivots mounted on said step, the pivots being in the same vertical plane but to the rear of the front face of the step, coiled springs surrounding said pivot and engaging the aforesaid arms to swing them 80 through an angle of substantially 180 degrees, projections extending downwardly from each arm the projections being of different lengths, resilient triggers mounted on said support and adapted to engage the projections to hold and release the same, leaf supporting clips adapted to slide on said arms, and transparent, vertical leaf supporting standards carried by said arms and adapted to lie beneath a sheet and turn the 90 same, when the carrying arm is released from its trigger.

2. A music leaf turner comprising a base block having a rabbeted front face forming a step at its lower end, leaf carrying arms 95 pivotally mounted on said block on vertical pivots, said pivots mounted on the step to the rear of its front face, springs carried by said pivots and acting on the arms to swing them through an angle of substantially 180 100 degrees, projections carried by said arms, resilient one piece triggers flexibly mounted in the base block and coacting with said projections to retain the arms in fixed positions and to release the same, a plurality of 105 leaf holding clips slidably carried on the arms, and a plurality of transparent upstanding spaced apart standards pivoted at their lower ends to the arms and adapted to lie beneath a sheet and turn the same when 110 its carrying arm is swung to the left.

In testimony whereof I have signed my name to this specification in the presence of two subscribing witnesses.

HERBERT JOHN BAILEY.
